(57) **CLAIM**

The ornamental design for a LED light lens, as shown and described.

DESCRIPTION

FIG. 1 is a front perspective view of a LED light lens; FIG. 2 is a top plan view thereof; FIG. 3 is a bottom plan view thereof; FIG. 4 is a right elevation view thereof, the left elevation view being a mirror image thereof; FIG. 5 is a front elevation view thereof, the rear elevation view being a mirror image thereof; and, FIG. 6 is a section view taken along line 6-6 in FIG. 2. The remaining broken lines shown in the drawings depict portions of the LED light lens that form no part of the claimed design.

1 Claim, 3 Drawing Sheets
